UNITED STATES PATENT OFFICE.

WILLIAM BRENNAN, OF NEW YORK, N. Y.

WIRE LATHING.

SPECIFICATION forming part of Letters Patent No. 228,030, dated May 25, 1880.

Application filed March 1, 1880. (No model.)

To all whom it may concern:

Be it known that I, WILLIAM BRENNAN, of the city, county, and State of New York, have invented a new and useful Improvement in 5 Supporting Wire Lathing, of which the following is a specification.

Figure 1 is a sectional elevation of the improvement. Fig. 2 is an under-side view, part being broken away.

10 Similar letters of reference indicate corresponding parts.

The object of this invention is to support wire lathing in ceilings in such a manner as to leave no air-spaces between the beams and the 15 mortar, which spaces, in case of fire, serve as draft-flues, and thus cause the fire to spread rapidly, and increase the difficulty of controlling the fire.

A represents the beams of a ceiling; and B 20 represents the wire-netting which serves as a lathing, and to which the mortar C is applied. The wire lathing B has heretofore been applied to furring attached to the beams A. This construction is objectionable, from the 25 fact that the mortar could not rise high enough above the wire lathing to fill the spaces between the said lathing and the beams, which

spaces, in case of fire, act as flues to draw the fire into and cause it to spread through the ceilings, rendering it very difficult for the firemen to get at the fire and control it. To remove this difficulty I attach iron rods D to the lower edges of the beams A transversely by means of staples E or other suitable means, and then attach the wire lathing B to the rods D by wires F or other suitable means. With 30 this construction the mortar C entirely fills the spaces between the lower edges of the beams A and the wire lathing B and surrounds the lower part of the beams A, so that there will 35 be no space for the passage of air between the beams and the mortar, and consequently fire cannot spread through the ceiling.

Having thus described my invention, I claim as new and desire to secure by Letters Patent—

A wire lathing secured to beams A by rods D, staples E, and wires F, as shown and described, for the purpose specified.

WILLIAM BRENNAN.
